CLAIM

The ornamental design for a note holder, as shown and described.

DESCRIPTION

FIG. 1 is a rear perspective view of a note holder showing my new design;

FIG. 2 is a front perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The uneven-length broken lines immediately adjacent to the shaded areas on the front face of the design and the bottom of the jointed stand of the design define the bounds of the claimed design and form no part thereof. The even-length broken lines depicting the remainder of the note holder form no part of the claimed design.
